UNITED STATES PATENT OFFICE.

REUBEN VOSBURGH, OF OREGON, ILLINOIS.

SASH-WEIGHT.

SPECIFICATION forming part of Letters Patent No. 276,509, dated April 24, 1883.

Application filed September 23, 1882. (No model.)

To all whom it may concern:

Be it known that I, REUBEN VOSBURGH, a citizen of the United States, residing at Oregon, Ogle county, Illinois, have invented new and useful Improvements in Sash-Weights, of which the following is a specification.

My invention relates to certain improvements in sash-weights, and particularly to that class known as "sectional weights." My invention has for its object to prevent any axial or rotary movement between adjacent weights, while they are at the same time protected against lateral displacement; and with this end in view my invention consists in forming one end of the weight with convex elevations concentric with the rope-channel, and one or more radial or intersecting concave depressions, and the opposite end with circular concave depressions and radial or intersecting convex projections adapted to interlock with the end of an adjacent section, as will be hereinafter explained.

In the accompanying drawings, Figure 1 is a perspective view of a section embodying my invention; Fig. 2, a central vertical section taken at the line $x x$ of Fig. 1; Fig. 3, a similar section of three weights strung upon a suspension-cord; Fig. 4, a plan view of the top or upper end of a section, and Fig. 5 a plan view of the opposite end.

Similar letters denote like parts in the several figures.

A represents a cast-iron sectional weight

having a central cord-channel, B, tapering from both ends toward the center, preferably 35 in curved lines, as most clearly shown at Figs. 2 and 3. The upper end or top of each section is formed with a raised circular rib, C, and one or more intersecting or radial depressions, D, while the opposite end or bottom is formed with a circular depression, E, and one or more radial or intersecting projections, F, so that when two or more sections are strung upon a suspension-cord, G, the projections and corresponding depressions, C E, and radial depressions and projections D F will interlock, respectively, and prevent not only lateral movement of the sections relative to each other, but will also prevent any independent rotary movement.

What I claim as new, and desire to secure by Letters Patent, is—

A sectional weight, A, having one end formed with circular projections C and radial or intersecting depressions D, and its opposite end with corresponding circular depressions, E, and intersecting or radial projections F, whereby lateral and axial movement is prevented, substantially as set forth.

In testimony whereof I have hereunto set 60 my hand in the presence of two subscribing witnesses.

REUBEN VOSBURGH.
